UNITED STATES PATENT OFFICE.

NATHAN H. LONG, OF MUNCIE, INDIANA.

RAIN-WATER FILTER.

SPECIFICATION forming part of Letters Patent No. 571,776, dated November 24, 1896.

Application filed May 9, 1896. Serial No. 590,893. (No model.)

To all whom it may concern:

Be it known that I, NATHAN H. LONG, a citizen of the United States, residing at Muncie, in the county of Delaware and State of Indiana, have invented certain new and useful Improvements in Rain-Water Filters; and I do hereby declare the following to be a full, clear, and exact description of the invention, such as will enable others skilled in the art to which it appertains to make and use the same.

This invention relates to improvements, as hereinafter set forth, in rain-water filters adapted to be attached to a building in connection with the rain-spout or gutter.

In the accompanying drawings, Figure 1 represents a perspective view of my improved filter. Fig. 2 represents a sectional side elevation thereof.

The object of my present invention is to produce an improved filter adapted to be removably connected at its upper portion to the ordinary rain-conveying spout depending from the eaves or roof-gutter of a building, and connected, with capability of ready removal, at its other end with a suitable cistern or tank, within which the filtered rain-water is received. The construction shown in the drawings, and to be presently described, results in the production of a filter which, while cheap in construction and capable of being readily placed in and removed from position; is automatically self-cleaning, automatically discharges all dirt and other foreign matter that may wash off the roof, and requires no filtering material other than the construction of the apparatus to secure the thorough filtration of the water passing through the apparatus.

1 represents the main chamber or body of the apparatus. This, as shown, is of vertical formation with a vertically-flat rear or back 2 to adapt it to rest against the wall or side of a house or other building, so as to be braced and steadied thereby.

3 represents a laterally-extending flange, of which there are two, one extending from each side edge of the body 1, having a vertical slot 4, through which is passed a screw 5 or other suitable device for removably and ad-

justably attaching the apparatus to a building.

The body 1 may be of any suitable metal or material, and has, preferably, its front upper portion extending angularly forwardly and downwardly, as shown at 6, and from 55 thence in a rearwardly angular direction, as shown at 7, whereby sufficient space is provided at its upper portion to receive the water-filtering and dirt-discharging shoe, to be presently described, and to provide space 60 for containing the reticulated filtering cylinder or tube and for receiving and guiding the water to said filtering cylinder or tube.

8 represents the water-filtering and dirt-discharging shoe, which is independent of 65 and removably contained within the upper, widest, portion of the body or chamber 1. This shoe may be retained in position, with capability of ready removal, in any suitable manner, as, for instance, by means of an up- 70 turned flange 9, extending from the hood 10 and engaging with a flange 11, extending downwardly from the top 12 of the body portion 1, and a downcurved flange 13 at its lower front edge gripping the front edge 14 75 of the body 1. This shoe has imperforate side walls 15, which snugly fit the inner sides of the body 1, and a concave and upwardly-curved rear reticulated portion 16, and a forwardly and downwardly curved reticulated 80 portion 17.

18 represents an upward extension dividing the reticulated portions 16 17 of the shoe and serving as a dam which, in connection with the flap or shutter 19, hinged at 20, operates to check the flow of water when the downfall is excessive. This dam also acts as a separator or stop for the dirt falling onto the shoe, the hinged shutter 19 being, however, sufficiently raised to permit of the inflow of water forcing the accumulated dirt across the front portion of the shoe and over the front edge thereof onto the ground. By the use and location of the flap or shutter, as shown, the same serves the additional purpose of preventing the descending water splashing out over the front of the shoe, but confines it measurably to the reticulated por-

tion of the shoe, so that it may descend into the chamber.

21 represents one of a pair of hooks connected with the flap or shutter, said hooks 5 engaging with eyes 22 to hold said shutter or flap and also aid in securing the shoe in position.

23 represents a vertical reticulated cylinder or tube frictionally supported at its lower 10 end 24 in the tube or pipe 25, through which the filtered water passes to the cistern or other receptacle. (Not shown.) This reticulated cylinder or tube 23 serves to additionally filter the water which has been preliminarily 15 filtered in its passage through the shoe 8, as all the water passing into the discharge-pipe 25 must first pass through said cylinder 23, as clearly indicated in Fig. 2.

26 represents a collar extending vertically 20 upward from the top 12 of the chamber or body 1 to receive and grippingly hold, as shown in Fig. 2, the lower end of a bifurcated or two-part pipe. Of this 26^a represents the section of said pipe through which water 25 passes from the upper section 27, which connects with the pipe (not shown) connecting with the gutter for carrying off the rain-water therefrom. The pipe-section 28, branching from the section 26, represents the waste-water-discharge pipe through which the rain-water discharging from the gutter or eaves-trough passes when the cistern is full or when for any other reason it is not desired to pass water through the filter.

29 represents a valve or shutter of preferably curved form, as shown, pivoted in the upper portion of the sectional pipe and operable by a handle or rod, as 30, to turn said valve in either direction desired to close 35 either section of said pipe, as shown in dotted lines in Fig. 1, to permit of the water descending from the roof passing down either branch 26 or 28 of the filter-supply pipe, as it may be desired to carry such water either 40 into the filter or through the waste-pipe.

Having thus described my invention, what I claim is—

1. A rain-water filter, consisting of a chambered body portion adapted to be attached to 50 a building, a pipe connecting said chambered body and the rain-water-supply pipe, a discharge-pipe connected with the lower portion of said body, a vertical reticulated chamber or tube seated in said discharge-pipe and extending up within said chamber, a shoe removably seated in the upper portion of said chambered body and having at its upper portion a depending hood, a dual-concaved and reticulated lower portion constituting the 55 bottom and rear, an upwardly-extending dam between said dual concaves, and a shutter 60

hinged on said shoe and rockingly depending above the reticulated portion thereof substantially as and for the purpose set forth.

2. A rain-water filter, consisting of a chambered body portion adapted to be attached to the side of a building and having at its top an upwardly-extending collar and at the upper portion of its front face an opening and a depending flange, a double-concaved reticulated shoe having a central transverse dam and removably contained within said open portion and extending across and upwardly of the upper portion of said chamber, a shutter hinged in and extending transversely across said shoe, a bifurcated or branched pipe connecting at its upper portion with the rain supply, one lower end of said pipe connecting with said collar and the other portion extending parallel with the chambered body 80 a curved valve pivoted in the upper portion of said branched pipe, a discharge-pipe extending from the bottom of said body, and a tubular strainer removably seated in said discharge-pipe and extending up within said chamber, substantially as and for the purpose set forth.

3. A rain-water filter adapted to be attached to a building and having connection with the rain-water supply, and consisting of a shell 90 or body and an outlet-pipe, a vertically-disposed chamber located within said shell or body and a shoe removably seated in the upper portion of said shell or body and having a reticulated bottom portion and a transverse bridge, or dam, and a shutter rockingly journaled in said shell and extending transversely of and above said shoe, substantially as and for the purpose set forth.

4. A rain-water filter, consisting of a shell 100 or body having a flat rear portion and a downwardly-tapering front portion, a water-discharge pipe connected with its lower end, a reticulated cylinder or tube removably seated at its lower end in said discharge-pipe, a shoe 105 removably seated in the upper portion of said shell and having a dual-concaved reticulated bottom and a substantially central upwardly-projecting bridge or dam, a shutter pivoted in said shell and located above said bridge or dam, a combined water-supply and waste-discharge pipe connected with the upper portion of said shell, and a cut-off valve located in said last-named pipe substantially as and for the purpose set forth.

In testimony whereof I affix my signature in presence of two witnesses.

NATHAN H. LONG.
